UNITED STATES PATENT OFFICE.

ARVID ANDERSSON LIND, OF STOCKHOLM, SWEDEN, ASSIGNOR TO ELEK-
TROMILITARA AKTIEBOLAGET, OF STOCKHOLM, SWEDEN.

VIBRATOR FOR SOUND-TELEGRAPH APPARATUS.

SPECIFICATION forming part of Letters Patent No. 786,041, dated March 28, 1905.
Application filed July 17, 1903. Serial No. 165,979.

To all whom it may concern:

Be it known that I, ARVID ANDERSSON LIND, a subject of the King of Sweden and Norway, and a resident of Stureparken 4, Stockholm, in the Kingdom of Sweden, have invented certain new and useful Improvements in Vibrators for Sound-Telegraph Apparatus, of which the following is a specification, reference being had therein to the accompanying drawings.

This invention relates to vibrators for sound-telegraph apparatus. As is well known, the vibrator comprises an electromagnet in which one end of the coil is connected with a spring-controlled armature which normally bears upon a contact, but when attracted interrupts the current in the said coil in the same manner as the armature in the galvanic bell. The said vibrator is by means of a key intermittently inserted into the primary circuit of an induction-coil—for instance, according to the Morse system—the secondary winding of which coil is connected with the telegraphic wires, alternating currents being thus created in the said wires each time the vibrator is caused to operate by means of the key, which currents are perceived as sounds by means of a telephone at the distant receiving-station. In such vibrators it very often happens that the armature, owing to imperfect adjustment or for other causes, is not sufficiently attracted to interrupt the current when the key is depressed. Consequently either no signals at all or incorrect signals are transmitted.

The main object of this invention is to obviate this disadvantage. For this purpose the vibrator is arranged to form the key proper of the apparatus, so that the armature is positively operated at each depression of the key, and thus under all circumstances is caused to vibrate, the subsequent vibrating motion being, as usual, effected by the electromagnet.

In the accompanying drawings the invention is shown applied to a combined telephone and sound-telegraph apparatus specially constructed for use in the army or in other service where the apparatus must be portable and occupy but small space.

Figure 1 is a side view and part longitudinal section of the apparatus. Fig. 2 is a front

view of the apparatus. Fig. 3 is an enlarged 50 sectional view of the upper part of Fig. 1. Fig. 4 is a diagram of the circuits.

In a casing or box 1 a dry battery 2 is mounted, provided at its respective ends with terminals 3 and 4. A contact-spring 5, fixed 55 to an insulating-disk 6 in a supporting-plate 7 in the casing, and a contact-spring 8, fixed to a cover 9, screwed on the said casing, bear against the terminals 3 4. The plate 7 is fixed at some distance from the upper end of the 60 casing, a chamber 17 being thus provided in which the induction-coil 10 is mounted. The cylindrical iron core 11 of the said coil is hollow, and the electromagnet 12 is loosely inserted into the same from the open end of the 65 core. The wire of the electromagnet is wound on a cup-like core 13, to the lower end of which is fixed an iron casing 14, inclosing the said electromagnet. The said casing is secured to the core by means of a screw 15, the 70 head of which forms a contact-piece. The core 13 is connected with one end of the said wire. Between the bottom of the casing 14 and the said screw-head is disposed an insulating-plate 16, and a similar plate 16^a is disposed above 75 said bottom and between it and a plate or disk which bears on the lower end of the magnet. A cap 18 is screwed on the top end of the casing 14 and bears a screw 19 for the adjustment 80 of the springy armature 20, which is fixed on the electromagnet and connected with the other end of its wire. Between the said screw 19 and the armature 20 is disposed a leaf-spring 21, which is fixed to the cap 18 and bent at an angle, as shown. The spring-armature 20 normally bears upon the free end of the said spring 21. By the said arrangement the armature 20 can be accurately adjusted by means of the screw 19. 22 is an 85 apertured cover screwed on the end of the 90 casing 1.

As will be seen from the above description, the electromagnet, its armature, and the adjusting-screw, which together constitute the vibrator, form a connected whole which is 95 movable in the hollow core of the induction-coil and can be removed from the same after the screwing off of the cover 22 for inspection

or the like. By the said arrangement the vibrator and induction-coil occupy a minimum of space. A spiral spring 23 is mounted between the inner wall of the core 11 and the electromagnet. The lower end of said spring 23 bears upon a flange 24 on the inner wall of the said core, and the top end of the spring presses against the edge of the cap 18. In this manner the spring 23 tends to move the vibrator outward. A cup-shaped push-button 25 is mounted in the aperture in the cover 22. The cap 18 supports the edge of the said button, which is retained in the cover by a flange 26 thereon. When the said push-button is pressed inward, it moves the vibrator 12 against the tension of the spring 23 until the head of the screw 15 strikes a contact 27, fixed in the disk 6 and connected electrically with the spring 5. The core 11 is connected with one end of the primary conductor of the induction-coil 10, the other end of which is connected with the contact-spring 8 through the wall of the casing 1. Thus as the head of the screw 15 strikes the contact 27 a current will pass from the battery-terminal 3 through the spring 5, the contact 27, the screw 15, the electromagnet 12, its armature 20, the spring 21, the cap 18, the core 11, the primary conductor, the wall of the casing 1, and the contact-spring 8 back to the battery. In this manner the electromagnet is excited. When the screw 15 strikes the contact 27 and the electromagnet 12 is consequently arrested, the armature 20, by reason of its inertia, will continue to move downward and leave the spring 21, which is stiffer than the springy armature, so that the vibrations of the armature are "initiated," so to say, and under all the circumstances will begin, such vibrations being then caused to continue by the electromagnet so long as the screw 15 is held in contact with the contact 27. When the button 25 is released, the vibrator and the button are moved outward by the spring 23. Thus it will be seen that the vibrator serves also as the key of the telegraph apparatus. The electromagnet is guided during its movement by a projection 32 on the inner wall of the core 11 engaging a slot 33 in the wall of the casing 14.

34 is a casing containing the receiver of the telephone apparatus, and 35 is a casing enclosing the transmitter of the said apparatus. The said casings are carried by tubes or bars 36 36 and 37 37, respectively, sliding telescopically in tubes 38 38 and 39 39, fixed to the casing 1, so that the receiver and transmitter can be drawn out a certain distance

and brought into the position shown in full lines when telephoning is to take place. On the contrary they can be pushed together so that the apparatus assumes a length no greater than that of the casing 1, as shown in dotted lines, Fig. 1. The ends of the secondary winding of the induction-coil are connected with clamping-screws 40 41, forming the line-terminals.

28, 30, 42, and 43 are contact-springs in a switching device acted upon by the vibrator (key) and serving to bring the receiver and transmitter out of and into action. The telephone apparatus and the said contact-springs are not particularly described, as they do not form any part of this invention.

Fig. 4 shows the electrical connections. When the parts are in the position shown in this diagram, telephoning can take place, a primary current flowing from the battery 2 through contact 28, contact 42, connecting-spring *a*, (at the transmitter,) the diaphragm 80 *b*, carbon particles *c*, the ring *g*, the shaft *d*, and the primary circuit of the induction-coil 10. When the electromagnet 12 is depressed for telegraphing, the receiver 34 is brought out of action by the circuit *e*, 30, 43, and *f*. The current through the transmitter is interrupted at 42. A primary intermittent current flows from the battery 2 through contact 27, core 13, armature 20, contact 21, cap 18, and the primary of the induction-coil 10. Induced currents then flow through *L*, the secondary of the induction-coil and the circuit *e*, 30, 43, *f*, and *L'*.

Having now described my invention, what I claim as new, and desire to secure by Letters Patent, is—

1. A vibrator for a sound-telegraph apparatus, having a guide, an electromagnet, its armature, and the contact for said armature, connected to form the key of the apparatus and mounted slidably in said guide.

2. A vibrator for a combined telephone and sound-telegraph apparatus, having a hollow iron core for the induction-coil of the telephone device, an electromagnet, its armature, and the contact for said armature, connected to form the key of the telegraph device and mounted slidably in said core.

In witness whereof I have hereunto signed my name in the presence of two subscribing witnesses.

ARVID ANDERSSON LIND.
